REINHARD B. BARTELS, OF MARBLEHEAD, MASSACHUSETTS

SHOE HAVING SHANK STIFFENERS AND METHOD OF MAKING SUCH SHOES

Application filed November 1, 1929. Serial No. 403,999.

This invention relates to shoes of those types which employ both inner and outer-soles, such as welt, McKay, Littleway process and cement process shoes and wherein it is desired to employ a stiffener for the shank portion of the shoe attached to the outer face of the innersole and more particularly where the shank stiffener is made from tempered steel. It has not been found practicable to provide tempered steel shank stiffeners with integral attaching prongs for fastening them to the sole members for the reason that the tempering has been found to cause the roots of the prongs to be too brittle to permit the prongs to be clinched in the sole members. Such shank stiffeners are provided therefore with perforations for the reception of separate fastening devices. Shoes of the types mentioned are commonly made on wood lasts which do not present suitable surfaces for clinching of the separate fastenings at the forward end of the stiffener. To insure adequate fastening of the stiffener, therefore, it would be desirable to fix the fastening to the innersole before its attachment to the last as at this time its upper face is accessible to suitable setting tools. If, however, the stiffener should be fixed in proper position on the innersole prior to the side lasting of the shoe, it would be in the way of the side lasting devices when operating at the relatively narrow shank portion of the shoe and it would thus interfere with this essential operation. It has been customary, therefore, to fix the stiffener in position as well as possible after the lasting operation and the great difficulty of fixing the stiffener securely in position at that time has been a serious objection to the use of tempered steel stiffeners.

The present invention has for an object to overcome this objection. To this end a fastener for the stiffener is provided which can be securely fixed to the innersole before it is applied to the last and when suitable setting tools may be engaged therewith, and the stiffener and fastener are so constructed and related that the stiffener is firmly secured at its forward end when in its normal position of use against the under or outer face of the innersole but can be retained out of that position and where it will not interfere with the lasting operation until this operation has been completed, whereupon it may be brought into its position of use and there easily secured. As the heel portion of a last is commonly provided with a metal face, no difficulty in properly clinching a separate fastening element at the heel end of the stiffener is ordinarily experienced and since a heel is later secured to this portion of the shoe, the firm fixing of this end of the stiffener in position is further facilitated. In accordance with this invention, therefore, the stiffener and fastener cooperate to provide a hinge connection for the stiffener at its forward end with the innersole, which permits the stiffener to be swung away from the shank portion of the shoe so long as its rear end is unattached, so that the side lasting may not be interfered with, and after the side lasting is completed the rear end of the stiffener is brought into its normal position of use against the innersole and there secured by appropriate means.

For a more complete understanding of this invention, reference may be had to the accompanying drawings in which Figure 1 is a plan of the top or inner face of an innersole showing the fastener for the forward end of the shank stiffener clinched therein. Figure 2 is a detail section on line 2—2 of Figure 1 showing the stiffener broken away. Figure 3 is a perspective of the stiffener. Figure 4 is a side elevation of the innersole with the shank stiffener secured thereto in condition to be fixed to the bottom of a last. Figure 5 is a perspective of the shoe after lasting, the stiffener being shown in position to permit side lasting. Figure 6 is a fragmentary view similar to a portion of Figure 5, but showing the rear end of the stiffener secured in position.

Referring to these drawings, 1 indicates an innersole to which the shank stiffener 2 is to be secured. This shank stiffener as shown in Figure 3 is provided with perforations 3 and 4 adjacent to its ends through which

fasteners may be placed. The opening or perforation 3 at the forward end of the stiffener is so positioned relative thereto as to form a pivot portion 5 between the opening 3, and the forward edge 6 of the stiffener. The fastener for securing this end of the stiffener comprises a strip having an intermediate loop portion 7, shown best in Figure 2, which is designed to engage about the 10 pivot portion 5 of the stiffener and end portions 8 and 9 which are bent away in opposite directions from the portion 7 and are then turned so as to be driven through the sole 1 as at 10 and 11, their pointed ends 13 and 14 being turned inwardly and clinched into the material of the innersole to fix the fastener in position. This fastener, with the stiffener engaged therewith, is fixed in position at the forward edge of the shank 20 portion of the sole adjacent to the break line before the sole is tacked to the last, as shown in Figure 4, the sole then being in flat condition and the fastener permitting the stiffener to be moved about the pivot portion 5 of 25 the stiffener between the full and dotted line positions shown in Figure 4. The sole with the stiffener thus attached at its forward end is then secured to the last and the upper is assembled therewith and lasted in 30 position while the stiffener 2 is positioned, as shown in Figure 5, with its rear end turned forwardly. When the stiffener is in this position it offers no obstruction to the wipers or other mechanism used in drawing over the 35 upper materials during the lasting operation, since it is not positioned against the sole surface at the shank portion of the shoe where the sole is narrowest. This lasting may be done in a manner suitable for the 40 particular type of shoe being made, whether welt, McKay, Littleway process, or cement process, that illustrated in Figure 5 being in accordance with the McKay, Littleway or cement process, and after this side lasting 45 has been completed, the stiffener may then be swung about its pivotal connection and its rear end secured to the innersole, as by driving a suitable fastener 15 through the perforation 4, this being clinched against 50 the usual metal facing for the heel end of the last. This completes the securing of the stiffener in position in the shoe, its manner of securing being effective to prevent movement of the stiffener in the completed shoe 55 by reason of the forces exerted thereon during service.

An embodiment of this invention having thus been described, it should be evident to those skilled in the art that various changes 60 and modifications might be made therein without departing from the spirit or scope of this invention as defined by the appended claims.

I claim:

65 1. In combination, a shoe sole, a shank

stiffener, and means for fixing one end of said stiffener to said sole adjacent to its break line against relative longitudinal displacement and for relative pivotal movement from and toward superposed facial contacting relation.

2. The steps in the manufacture of a shoe having an innersole and a shank stiffener fixed thereto, which comprise pivotally fixing the forward end portion of the stiffener to the innersole, fixing the sole and stiffener to a last, assembling an upper on the last, lasting the upper to the innersole including lasting the shank portion while the rear end of the stiffener is swung away from the shank portion of said innersole about its pivotal connection with said innersole, bringing the rear end of said stiffener to its proper operative position relative to said innersole and securing it in position, and then completing the shoe.

In testimony whereof I have affixed my signature.
